(57) **CLAIM**

The ornamental design for a vehicle seating assembly, as shown and described.

DESCRIPTION

FIG. 1 is perspective view of a vehicle seating assembly showing our new design.

FIG. 2 is a front elevational view thereof.

FIG. 3 is a left side elevational view thereof.

FIG. 4 is a rear elevational view thereof.

FIG. 5 is a right side elevational view thereof.

FIG. 6 is a top plan view thereof.

FIG. 7 is a bottom plan view thereof; and,

FIG. 8 is perspective view thereof, showing, in exploded perspective format, the context of use thereof.

The broken line shown in FIG. 8 is for illustrative purposes only and forms no part of the claimed design.
